UNITED STATES PATENT OFFICE.

JOHN WICKSTROM, OF CHICAGO, ILLINOIS, ASSIGNEE, BY DIRECT AND
MESNE ASSIGNMENTS, TO JOHN T. FANNING, OF SAME PLACE.

HOT-AIR ENGINE.

SPECIFICATION forming part of Letters Patent No. 650,576, dated May 29, 1900.

Application filed April 26, 1898. Serial No. 678,838. (No model.)

To all whom it may concern:

Be it known that I, JOHN WICKSTROM, of Chicago, in the county of Cook and State of Illinois, have invented certain new and useful Improvements in Hot-Air Engines; and I do hereby declare that the following is a full, clear, and exact description thereof, reference being had to the accompanying drawings, and to the letters of reference marked thereon, which form a part of this specification.

This invention relates to improvements in hot-air engines of that class which are provided with a power-piston and with a transfer-piston which is actuated from said power-piston to transfer the air from the hot-air chamber to the cooling-cylinder, and vice versa.

The invention relates more particularly to an improved connection between the power-piston and crank-shaft and between the latter and the transfer-piston and to an improved construction of the power-piston by which the air is more effectively cooled while it is being transferred from the hot-air chamber to the cooling-cylinder and also by which air is more effectively used by reducing the cool clearance-space in the engine during the expansion of the air therein.

The invention relates, further, to other improvements in engines of this character, as will hereinafter more fully appear.

In the drawings, Figure 1 is a view, partly in side elevation and partly in vertical section, of an engine constructed in accordance with my invention. Fig. 2 is a view, partly in front elevation and partly in section, taken on line 2 2 of Fig. 1. Fig. 3 is a perspective detail of one of the connecting parts between the piston and crank-shaft. Fig. 4 is a diagram showing the relative positions of the different parts of the engine at the various positions of the crank-arm in the revolution thereof.

In said drawings, A designates a base casting or support which sustains the various operative parts of the engine, said casting being sustained upon legs A'.

B designates a power-cylinder, which serves also as a cooling-cylinder; B', a piston therein; C, a hot-air chamber; D, a burner for heating said chamber, and E a transfer-piston which reciprocates in said cylinder and

hot-air chamber. D' designates as a whole a vaporizing device which supplies fuel to said burner. The hot-air chamber is connected with the power-cylinder through an intermediate cylinder C', which is hereinafter considered as a part of the hot-air chamber, and such chamber and intermediate cylinder and power-cylinder are connected together in axial alinement by bolts passing through outwardly-extending radial flanges thereon, as shown. Said hot-air chamber and power-cylinder are sustained in vertical position, as herein shown, upon the bed A in any suitable manner; the bed being provided with a circular opening through which the lower end of the hot-air chamber depends. Said lower end of the hot-air chamber is surrounded with a casing which directs the heat to said chamber and prevents its radiation therefrom. Said casing consists in the present instance of an inner lining C², of asbestos or other suitable non-conducting material, and an outer covering C³, of sheet metal, which is attached to the bed or base casting A in any suitable manner. Said casing is provided in its bottom with an opening through which the burner D extends and will be provided with an exit-pipe (not shown) for the escape of the products of combustion.

F designates a crank-shaft, which is connected with and driven by the piston B'. The connecting means consists of an intermediate sector-shaped rocking lever G, which is pivoted at its vertex to a stationary standard A², connected rigidly in any suitable manner to the bed-plate A, a pitman G', which connects said rocking lever to the crank-arm F' of the crank-shaft, and a connecting-rod G², which is pivoted at one end to an extension G³, attached to or formed integral with said lever and which is pivoted at its other end to the piston.

The transfer-piston E is operated from the crank-shaft by means which give it a variable motion with respect to the power-piston. The driving means between the transfer-piston and the crank-shaft consists of a rocking lever H, which is pivoted to the upper end of the standard A² to swing in a vertical plane between said rocking levers G and G', which is connected to an arm G⁴, formed rigid with the pitman G' and at an angle thereto,

as herein shown, by means of a connecting-link H'. Said rocking lever H is connected at its outer end by means of a link H² with a connecting-rod H³, which latter is attached 5 at its opposite end to the transfer-piston inside of the power-piston, said connecting-rod passing through a stuffing-box b in said power-piston.

The power-piston fits closely within the 10 cylinder B, (which is in this instance open at its outer end,) so as to prevent the escape of air past the same, and is provided on its inner side with a rigid sleeve B², which extends into the intermediate cylinder C'. Said sleeve 15 is of less external diameter than the piston proper, thereby forming between the same and the inner wall of the power-cylinder when the power-piston is moved outwardly, so that a portion of the sleeve occupies said cylinder, 20 an annular space, as indicated at b'. The lower end of the power-cylinder is reduced in diameter, as indicated at b², so that the sleeve B² fits closely therein at this point to form an air-tight joint. Conveniently the piston will 25 be made of two parts—an upper part B³, to which the connecting-rods G² are attached, and a lower part B⁴, with which the sleeve B² is integrally cast. Said lower part of the piston 30 is of less diameter than the upper part thereof, and a packing b³ is interposed between the same and the cylinder and is held in place between the upper and lower plates forming said piston.

The transfer-piston consists of a hollow cylindrical shell, which is desirably formed from sheet metal by a drawing operation and is made of such diameter as to fit closely within the inwardly-extending sleeve B² of the power-piston. Said transfer-piston is made 35 air-tight, the inner end thereof being formed integral with the body of said shell and the outer end being formed by means of a cast-metal disk E', which is fitted closely within the outer end of the shell and secured permanently therein in any suitable manner. The metal of the piston is braced from inward distortion from external pressure of the air by means of internal transverse rings E², secured rigidly thereto. Said transfer-piston 40 is made of considerable length in order to separate the hot-air chamber from the power or cooling cylinder a sufficient distance to prevent the conduction of heat from said hot-air chamber to said cylinder. In order to 45 further insulate the power-cylinder from the hot-air cylinder, disks E³, of asbestos or like non-conducting material, are laid upon the strengthening-rings E². Communication is established between said hot-air chamber and power-cylinder and inside of the power-piston 50 by means of a passage C⁴ in the wall of the intermediate cylinder C', which opens at one end into an annular recess b⁵ in the inner wall of the power-cylinder between the 55 point therein occupied by the piston when at the limit of its inner stroke and the reduced portion b² and in communication with the

annular cooling-space b', and which passage C⁴ opens at its opposite end into an annular recess c in the intermediate cylinder C'. The 70 outer end of the sleeve B², adjacent the power-piston, is provided with a circular series of ports b⁶, through which the air enters from the annular cooling-space b' after it has been cooled by contact with the walls of said power-cylinder to the space between said power-piston and the transfer-piston. Said passage 75 C⁴ contains a body of air which acts to transmit the pressure from the hot-air chamber to the power-cylinder, and said passage acts 80 also to convey air from the hot-air chamber to the power-cylinder, and vice versa, when displaced by the transfer-piston. The transfer-piston is operated at the completion of the outward stroke of the power-piston to 85 displace the heated and expanded air in the hot-air chamber and to force it through the regenerative passage C⁴ and through the cooling-space b' in the power-cylinder to the space 90 between the power and transfer pistons and to force said air from said cylinder after it has become cooled and preceding the next power-stroke to the hot-air chamber in order that it may be again heated.

The lower end of the hot-air chamber is 95 provided interiorly with a cylindric casing or lining C⁵, which fits at its upper end closely into the lower end of the intermediate cylinder above the annular recess c, into which the passage C⁴ opens, and is made of such external diameter in its part below said recess as to provide between the same and the inner wall of the chamber an annular space c', which is termed a "heating-space," through 100 which the air passes to the lower end of the hot-air chamber, and which space communicates with the interior of said casing C⁵ through a port c² at the lower end of the casing. Said annular heating-space c' is provided for the purpose of causing the air to be 105 spread out in a thin sheet in contact with the heated inner walls of the hot-air chamber in its passage to the lower end of said chamber, so that its temperature will be more rapidly 110 raised than if it were introduced at once into 115 said chamber in a relatively-large body.

As a means for reducing the temperature of the air as it passes from the hot-air chamber to the power-cylinder a regenerative device I, consisting of a plurality of longitudinally-arranged fine wires, is placed in the passage C⁴, the small wires forming said regenerative device acting to absorb a large portion of the heat of the air when passing therethrough from the hot-air chamber. Said heat is retained in the regenerative device, and when the cold air is forced in the reverse direction through said passage said air will absorb the heat held by said device and will therefore enter the annular heating-space c' in a partially-heated condition.

The operation of the engine is such, as will hereinafter more fully appear, that when the transfer-piston is being moved to displace the

air in the hot-air chamber and force it to the power-cylinder the power-piston will be near the outer limit of its power-stroke, so that the air which is driven from said hot-air chamber in order to enter the port b^6 to the space between said power-piston and transfer-piston will need to pass through the annular cooling-space b' , which is at this time increased in length over that shown in the drawings, owing to the movement of said piston outwardly, so that the air will be directed in a thin sheet against a relatively-long cold surface of the power-cylinder and will be thereby further cooled. The walls of the power-cylinder are provided with a water-space B^6 , through which cold water is forced and by means of which said walls are maintained cold. $b^{10} b^{11}$ designate, respectively, the inlet and outlet passages to said space. V designates a pump-cylinder; V' , a pitman or connecting-rod which is connected at its lower end with a piston (not shown) in said cylinder; V^2 , a sliding head which slides in vertical guides V^3 , located on standards V^4 on the base-plate A , and which head is connected with the pitman V' ; V^5 , a connecting-rod which is connected at one end with said head and at its other end with a crank V^6 , which is connected with a gear-wheel V^7 , mounted on a shaft V^8 , supported on said standards V^4 , and which gear-wheel meshes with a gear-pinion V^9 on the crank-shaft F . Rotation of said pinion and gear-wheel serves through the crank V^6 to give motion to the head V^2 and therethrough to the pump-piston.

The operation of the engine made as thus described will be best understood by reference to the diagram shown in Fig. 4 and will be explained in connection therewith. In said diagram the circular path of the crank-arm is indicated by F^a and is divided into twelve equal parts and numbered from 1 to 12, inclusive. The paths of the pistons, the levers G and H at their points of connection with the connecting-rods D^2 and H^3 , the pitman G' at its point of connection with the lever G , and the arm G^4 at its point of connection with the link H' , by which it is connected with the lever H , are also indicated, and the lines indicating the same are divided into twelve parts to indicate the positions of these various parts in their paths of movement during each one-twelfth revolution of the crank-arm. The diagram indicates the positions of the parts of the engine, as shown in Fig. 1—that is to say, with the piston at the beginning of its outward or power stroke under the impulse of the expanding air. In said diagram, P indicates the direct line on which the pistons travel; G^a , a line which passes through the upper member of the sector-shaped lever G and the projection G^3 thereof; H^a , the center line of the lever H ; G^b , the center line of the pitman G' ; G^c , the center line of the arm G^4 ; and H^c the center line of the link H' . A^a indicates the point of pivotal connection of the lever G with the standard A^2 , and A^b the

point of connection of the lever H with said standard. H^d indicates the arc through which the end of the lever H moves; G^d , the arc through which the extension G^3 of the lever G moves; G^e , the arc through which the lower member of the sector-shaped lever G at its point of attachment with the pitman G' moves, and G^f the curved path through which the outer end of the rigid arm G^4 of the pitman moves. The line P is divided into twelve parts to indicate the different positions of the power-piston to correspond to the divisions in the circular path of the crank-arm and is divided into twelve other parts to indicate the corresponding positions of the transfer-piston. The positions of said pistons in the return stroke are shown on the right-hand side of the line, and the positions in the outward or power stroke are indicated on the left-hand side of said line. The different positions of the power-piston are further indicated by the shorter lines having the prefix P and the transfer-piston by the longer lines and designated by the prefix T . The lines indicating the movements of the levers H and G and the extension G^3 of said latter lever, as well as the curved line which indicates the movement of the outer end of the rigid arm G^4 of the pitman G' , are similarly divided. From an inspection of the diagram it will be seen that the piston moves from the outward to the inward limit of its stroke during seven-twelfths of the revolution of the crank-arm. It will also be seen that from the position shown, in which the piston is beginning its outward movement under the influence of the expanding air, the transfer-piston and the inner face of the power-piston are almost in contact with each other and that they move toward the outer end of the cylinder in substantially the same relation, being separated only a slightly-greater distance at the limit of the outward stroke of the transfer-piston than at the point indicated as to the positions of the pistons in the diagram. This result is secured by the relation of the rigid arm G^4 to the pitman and to the points of pivot of the levers G and H during that part of the revolution of the crank-arm in which the power-piston is accomplishing its effective work, said arm at this time occupying such position with relation to the other parts that the movement given by the power-piston to the crank-shaft will be transmitted uniformly from said shaft to the lever H , so that said lever will move parallel with the lever G . When the crank-arm has passed through the arc of its revolution mentioned, the arm G^4 of the pitman will be oscillated laterally, owing to its angular relation with the pitman, which will act through the link H' to move the lever H and connected transfer-piston downward more rapidly than the power-piston. This arrangement of the driving means is such that the transfer-piston reaches the limits of its outward movement before the power-piston and begins its return stroke before the

power-piston has completed its power-stroke, so that the distance between said pistons at the beginning of the return stroke of the power-piston is increased, as indicated by the 5 distance between P' and T' on the line P. In the further revolution of the crank-arm the speed of the transfer-piston with relation to the power-piston is greatly accelerated, as indicated by the lines T' T² T³, &c., thereby 10 providing a space between said power and transfer pistons to receive the air which is displaced by the latter piston in the hot-air chamber and forced through the passage C⁴ to said space. The air which is driven from 15 said hot-air chamber and which is highly heated gives off a portion of its heat as it passes through the regenerative device I, and when it comes in contact with the cool surface of the cylinder as it passes through the annular 20 cooling-space b' between said cylinder and the sleeve of the piston and before it enters the space between the transfer and the power pistons is further reduced to about the normal temperature of the surrounding atmosphere. It will be noted by an inspection of 25 the diagram that the inward displacing stroke of the transfer-piston is accomplished in the first five-twelfths of the revolution of the crank-arm, while the return stroke of the 30 power-piston is not completed until the crank-arm has passed through seven-twelfths of its revolution. During the time the crank-arm is passing through the space from the fifth to the eighth twelfth of its revolution the transfer and power pistons are moving toward each 35 other and the air which is between the same is at this time forced through the passage C⁴ to the hot-air chamber. The direction of the power-piston is reversed just before coming 40 in contact with the transfer-piston, and the connections between the crank-shaft and the transfer-piston are such that the latter will assume the relation to the power-piston shown in Fig. 1 at the instant the crank-arm has 45 passed its lower center, so that at this time all of the air will be forced from the cool space between said pistons and driven to the hot-air chamber. The air on passing through the regenerative device will absorb the heat re- 50 tained thereby from the air during its last passage therethrough and will be spread in a thin sheet in contact with the heating-surface of the annular heating-space c', so that it reaches said hot-air chamber in a heated condition. 55 The air while being forced into the hot-air chamber and just before the crank-arm has passed its lower center will be placed under compression by the addition of heat thereto, so that when the crank passes its lower center the pressure of the air within the hot-air chamber will act to force the piston outwardly. The further heating of the air within the hot-air chamber will cause it to further expand and drive the power-piston outwardly 60 in the manner before stated.

The means herein shown for driving the transfer-piston from the crank-shaft possesses

great simplicity over driving connections heretofore employed for this purpose, as by the means shown said transfer-piston is more 70 directly connected with the crank-shaft, which insures prompt and efficient action thereof. Furthermore, the connecting part G⁴ between the pitman and lever H being rigid with the pitman and bearing a definite relation to said pitman enables the rocking levers H and G, which are directly connected with the transfer and power pistons, to be maintained in parallel relation during that part of the revolution of the crank-arm in which the effective part of the stroke is being made, so that 75 said pistons move outwardly together until the power-piston is near the end of its power-stroke, when the lateral oscillation of said rigid part G⁴ will act to move the lever H and piston E quickly downward to effect the displacement of the heated air in the hot-air chamber. The arrangement described enables the movement of the transfer-piston to be controlled with great precision, so that said 80 transfer-piston may be moved outwardly, together with the power-piston in the power-stroke of the latter, and be moved inwardly to displace the hot air in the hot-air chamber and returned in contact with the power-piston 85 when the latter begins its next power-stroke. The construction described wherein the power-piston is provided with an inwardly-projecting sleeve in which the outer end of the transfer-piston fits and slides is of great 90 importance, for the reason that it enables the annular cooling-space b' to be regulated independently of the movement of the transfer-piston, so that a large portion of the air from the hot-air chamber will be forced through the 95 annular cooling-space b' before its length has been materially reduced, thereby effectually cooling the air. Obviously if no sleeve were provided having inlet-ports, as b⁶, adjacent to the power-piston the length of the cooling- 100 surface with which the air is brought into contact as it passes between the power and transfer pistons would decrease in the same proportion as the transfer-piston is moved inwardly, it being evident that the air would 105 not pass beyond the outer end of the transfer-piston. Furthermore, said construction 110 permits the cool clearance of the engine to be reduced to a minimum at the beginning of the power-stroke of the piston, so that the power 115 of the expanding air can be most advantageously employed.

It will be understood that while the cylinder B has been termed a "power-cylinder" it also performs the function of a cooling-cylinder and that this double function will always be understood in connection with the cylinder.

The construction herein shown is a practical embodiment of my invention and for some reasons a preferred one; but I do not 125 wish to be limited to the details thereof, except as made the subject of specific claims.

I claim as my invention—

1. In a hot-air engine, the combination of a

power-cylinder, a hot-air chamber, a piston in said power-cylinder, provided with an inwardly-extending sleeve, a transfer-piston between the power-cylinder and hot-air chamber and sliding in said sleeve, and means connected with the power-piston for driving said transfer-piston.

2. In a hot-air engine, the combination of a power-cylinder, a hot-air chamber, a piston in said power-cylinder provided with an inwardly-extending sleeve, ports in said sleeves adjacent to the piston, a passage leading from said hot-air chamber and connected with said ports, a transfer-piston between the power-cylinder and hot-air chamber and sliding in said sleeve, and means connected with the power-piston for driving said transfer-piston.

3. In a hot-air engine, the combination of a power-cylinder, a hot-air chamber, a piston in said power-cylinder provided with an inwardly-extending sleeve which is of less external diameter than said piston and which fits closely within the lower end of said cylinder, ports in said sleeve adjacent to the said piston, a passage leading from the hot-air chamber and connected with said ports, a transfer-piston between said power-cylinder and hot-air chamber and sliding in said sleeve, and means connected with the power-piston for driving said transfer-piston.

4. In a hot-air engine, the combination of a power-cylinder, a hot-air chamber, a piston in said power-cylinder provided with an inwardly-extending sleeve which is of less external diameter than said piston and which fits closely within the lower end of said cylinder, ports in said sleeve adjacent to said piston, a transfer-piston between said power-cylinder and hot-air chamber and sliding in said sleeve, a passage external to said sleeve connecting said hot-air chamber and the power-cylinder outside of said sleeve, and means connected with the power-piston for driving said transfer-piston.

5. In a hot-air engine, the combination of a power-cylinder, a hot-air chamber, a piston in

said power-cylinder provided with an inwardly-extending sleeve, ports in said sleeve adjacent to said piston, a transfer-piston between said cylinder and hot-air chamber 50 which closely fits in said sleeve of the piston, a passage external to said sleeve connecting the said cylinder and hot-air chamber, a regenerative device in said passage and means connected with the power-piston for driving 55 the transfer-piston.

6. In a hot-air engine, the combination with a power-piston provided with an inwardly-extending sleeve, of a transfer-piston fitting and sliding in said sleeve as and for the purpose set forth.

7. In a hot-air engine, the combination with a power-cylinder and a hot-air chamber, of a piston provided with an inwardly-extending sleeve which is of less external diameter than 65 the internal diameter of the power-cylinder, a transfer-piston between the power-cylinder and hot-air chamber, and means for driving said power and transfer pistons.

8. In a hot-air engine, the combination with 70 a power-cylinder and a hot-air chamber, of a piston in said cylinder provided with an inwardly-extending sleeve which is of less external diameter than the internal diameter of the power-cylinder, a transfer-piston fitting 75 and sliding in said sleeve, a passage connecting said hot-air chamber and the space between the piston-sleeve and the wall of the power-cylinder, said sleeve being provided with a port connecting said space with the 80 space between the power-piston and transfer-piston, and means for driving said power and transfer pistons.

In testimony that I claim the foregoing as my invention I affix my signature, in presence 85 of two witnesses, this 22d day of April, A. D. 1898.

JOHN WICKSTROM.
